UNITED STATES PATENT OFFICE

2,524,596

LINE MARKER

Paul B. Kamp, Wolf Point, Mont., assignor to
Strate-Line Company, Williston, N. Dak., a corporation of North Dakota

Application May 20, 1949, Serial No. 94,320

3 Claims. (Cl. 33—86)

1

This invention relates to a tool the primary object of which is to permit one to make a straight chalk line mark on various materials, such as linoleum, where a separation or cut is to be made.

An important object of this invention is to provide a tool which is relatively simple in design and construction, cheap to manufacture in large quantities, and easy to manipulate to obtain an accurate and straight chalk line so that material may be quickly and accurately cut into desired lengths without unnecessary wastage of material.

A further object of this invention is to provide a line marker of the character described including a graduated measuring scale to determine the exact position where the chalk line should be applied to the material.

Yet another object of this invention is to provide a line marker comprising an elongated base member having a reference notch intermediate its ends and a measuring scale across its length, a flexible V-shaped member terminally secured adjacent the ends of said base member, an index on the apex of said V-shaped member, a chalk line, and means for securing one end of said chalk line to said base member adjacent said notch.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of the device;

Figure 2 is a sectional view taken substantially in the plane of section line 2—2 of Figure 1;

Figure 3 is a sectional view taken substantially in the plane of section line 3—3 of Figure 1.

Specific reference is now made to the drawings. In the several views in the accompanying drawings and in the following specification reference characters indicate corresponding elements throughout.

Indicated generally at 10 is a base member, preferably fabricated of rigid metal, and generally U-shaped as shown in the drawings. The base member is elongated and includes a lower leg 12 connected by a web portion 14 to an upper leg 16. Both legs are relatively flat, and the work to be marked, such as a piece of linoleum 18 is adapted to be received in the base member between the legs 12 and 16, the leg 12 underlying and the leg 16 overlying the linoleum as shown clearly in Figure 1. It will be understood at

this point that the web portion 14 may be of any desired length to accommodate work pieces of different thicknesses.

Intermediate the ends of the upper leg 16, a reference or V-notch 20 is provided and extending across the length of the upper leg 16 is a graduated measuring scale 22 for determining exactly where a chalk line is to be applied to the work piece 18.

10 A resilient, relatively flat V-shaped member 24 is provided, preferably fabricated of flexible steel, which is terminally secured by riveting or welding as at 26 to the ends of the upper leg 16 of the base member 10. The apex 28 of the V-shaped member 24 includes a protuberance 30 serving as an index as will be described hereinafter.

Secured as by welding or riveting to the underside of the lower leg 12 is an elongated, substantially U-shaped bracket 32, the shorter leg 34 of which is provided with an aperture 36 for receiving the eye 38 at one end of a chalk line 40. It will be noted that the bracket 32 is secured to the base member 10 in alignment with the reference notch 20.

In practical operation, the base member 10 is positioned on the work piece or linoleum 18 as shown clearly in Figure 1 and the chalk line 40 is secured to the bracket 32 at one of its ends. 30 The chalk line is then extended across the base member, intersecting the reference notch 20 and is then positioned beneath the apex 28 where it is held in position with reference to the index 30 by one of the hands 42. The chalk line 40 is extended in a taut position across the tool and the base member is moved to the position desired for marking as determined by the measuring scale 22 on the base member. Thereafter, the chalk line 40 is snapped with the fingers of the other hand 44 to deposit a chalk mark across the work piece 18 at the desired position. The flexibility of the V-shaped member 24 permits the latter to lie relatively flat against the work piece while the entire tool is retained in a more or less fixed adjusted position on the work piece by means of the U-shaped base member 10.

In view of the foregoing description taken in conjunction with the accompanying drawings it is believed that a clear understanding of the device will be quite apparent to those skilled in this art. A more detailed description is accordingly unnecessary.

It is to be understood, however, that even though there is herein shown and described a preferred embodiment of the invention the same

is susceptible to certain changes fully comprehended by the spirit of the invention as herein described and the scope of the appended claims.

Having described the invention, what is claimed as new is:

1. A line marker comprising an elongated base member having a reference notch intermediate its ends and a measuring scale across its length, a flexible V-shaped member terminally secured adjacent the ends of said base member, an index 10 on the apex of said V-shaped member, a chalk line, and means for securing one end of said chalk line to said base member adjacent said notch, said base member being a flat U-shaped bar having a relatively wide leg adapted to underlie a piece of work to be marked and a relatively narrow leg adapted to overlie a piece of work, said narrow leg including said notch and said measuring scale.

2. The combination of claim 1, wherein said 20 one end of the chalk line includes an eye and

said means includes a laterally extending apertured bracket carried by said base member at said notch for receiving said eye.

3. The combination of claim 2, wherein said 5 V-shaped member is substantially flat.

PAUL B. KAMP.
